UNITED STATES PATENT OFFICE.

JESSE E. McBRIDE, OF DETROIT, MICHIGAN, ASSIGNOR TO PALMER-BEE COMPANY,
OF DETROIT, MICHIGAN, A CORPORATION OF MICHIGAN.

CONVEYER.

1,418,590.

Specification of Letters Patent. Patented June 6, 1922.

Application filed July 14, 1919. Serial No. 310,832.

To all whom it may concern:

Be it known that I, JESSE E. McBRIDE, a citizen of the United States of America, residing at Detroit, in the county of Wayne, 5 and State of Michigan, have invented certain new and useful Improvements in a Conveyer, of which the following is a specification, reference being had therein to the accompanying drawings.

10 The invention relates to conveyers of that type designed for the transportation of a suspended load and the invention consists in various features of improvement as hereinafter set forth.

15 In the drawings:

Figure 1 is a side elevation showing a portion of the conveyer and one of the sprockets around which it passes;

20 Figure 2 is a plan view of one of the links showing the load-supporting roller and the connection with the cross bar for suspending the load.

Figure 3 is a side elevation of Figure 2;

25 Figure 4 is a cross-section on line 4—4 of Figure 2.

With the type of conveyer which my improvement provides the load is supported upon cross-bars extending between a pair of parallel conveyer chains. It is desirable 30 to provide roller supports for the load and heretofore various constructions have been devised with this in view. In one construction a supporting track is arranged outside of the line of the chain and the cross-bars 35 are extended over the track and supported by roller bearings. This has the disadvantage of increasing the width of the structure over that required for the transportation of the work. In another construction 40 the roller or wheel supports are arranged concentric with the pivots for adjoining links of the chain, the supporting track being in the plane of the chain. The objection to such a construction is that the driving 45 sprocket for the chain must engage the latter through the medium of the rolls. Therefore, it is necessary to design such rolls to carry the maximum stress upon the chain, which is many times greater than the load which is 50 supported by each individual cross-bar.

Another difficulty which has been encountered is the use of roller bearings so as to maintain the same lubricated and to avoid the dropping of dirt or dust from the bearings upon the work transported. This is 55

particularly objectionable in conveyers used in connection with enameling ovens inasmuch as the enamel finish is injured by the slightest deposit of dust or dirt while the enamel is still soft.

60 To overcome the above described difficulties I have designed a construction in which the load is supported by rollers in the line of the chain but which are not subjected to stresses transmitted longitudinally through the chain. I have further devised a construction in which the rolls may be successfully operated without the use of lubricant, thereby avoiding the creation of any dirt or dust which might injure the 65 work. Other features of improvement will be referred to hereinafter.

As shown in detail in Figures 2, 3 and 4, the conveyer chain comprises alternate links A and B which are pivotally connected to 70 each other by the pins C. The link B is preferably formed of a pair of straight bars which embrace the end portions D of the link A, said end portions constituting hollow pins or bearings for receiving the pivot pin 75 C. The link A intermediate the end portions D is provided with laterally offset side bars substantially aligned with the side bars of the link B and providing between them the clearance for a roller E. This roller is 80 adapted to run upon a track F and provided with a flange G at its outer end for holding it in engagement with the track. The inner side bar of the link A is formed with a laterally extending bearing H provided with 85 a cap I secured by clamping bolts J and this bearing is adapted to receive the cross bar K which, as shown, is tubular.

90 To lessen the friction of the roller E and at the same time to avoid the use of a lubricant, said roller is itself provided with a roller bearing L arranged in a recess therein and engaging a stationary pin M, which extends across between the side bars 95 of the link A. The roller bearing L is preferably of the type having resilient hollow rolls and by reason of the fact that the movement is comparatively slow such a bearing will operate satisfactorily without lubricant. The bearing is held from endwise displacement by the side bars of the link A and the parts are assembled by inserting the pin M through the registering apertures in the side bars and the bearing. The pin is then 100 locked from endwise displacement prefer- 105

ably by a flange N on the cap member I which engages a slot O in the pin. This also serves to hold the pin from rotation.

The link A is strengthened by cross webs 5 P merging into the end portions D and into the side bars at the bends thereof. These webs form cross struts which resist any tendency towards pulling of the offset sides inward under the longitudinal stress upon 10 the chain. In passing about the sprocket Q the sprocket teeth engage only the spaces in the links B but bear against the ends D of the links A to which the driving stress is directly applied. Thus, the rollers E are 15 not subjected to the longitudinal stress upon the chain and can be made of only sufficient strength to safely carry the load upon the cross bars K. The sprocket Q is cut away at R to provide clearance for the rolls E. 20 With the construction as described in operation when the chain is traveling over the tracks F, the load which is carried by the cross bars K, as well as the weight of the chain itself, is supported by the tracks 25 through the medium of the rollers E and resilient roller bearings L. On the other hand, the longitudinal stress upon the chain, which is usually many times greater than the load upon any individual link, is transmitted 30 from link to link through the pin C and co-operating bearings, these being properly designed to safely carry the stress. The roller bearings L reduce frictional resistance to a minimum while the absence of lubricant 35 avoids the dropping of dirt from the bearings upon the transported work.

What I claim as my invention is:

1. In a conveyer, the combination of a series of pivotally connected links, one of 40 said links having spaced side bars intermediate the pivots thereof with one side bar provided with a laterally offset portion intermediate its ends, and a load-supporting roller mounted between said spaced side bars 45 and at the side of said laterally offset portion.
2. In a conveyer, the combination of a series of pivotally connected links, one of said links having a load-supporting roller 50 mounted thereon intermediate the pivots thereof, and a sprocket for driving said links cut away in registration with said load-supporting roll to provide clearance therefor.
3. In a conveyer, a chain comprising a series of pivotally connected links, spaced 55 links thereof being provided with spaced side bars having laterally offset portions, and load supporting rollers mounted between the laterally offset portions of said spaced side bars.
4. In a conveyer, a link having end portions pivotally connected with adjacent links, spaced side bars intermediate and integral with said end portions, one of said side 60

bars having a laterally offset portion, and a load-supporting roller mounted between said spaced side bars and located at said laterally offset portion.

5. In a conveyer, a link having end portions formed with hollow bearings for receiving the pivots connecting said link to adjacent links, spaced side bars between said end portions laterally offset, and a load-supporting roller mounted between the offset 75 portions of said spaced side bars.

6. In a conveyer, a link having end portions for pivotal connection with adjacent links, spaced side bars intermediate said end portions, one of said side bars having a laterally offset portion, a load-supporting roller mounted intermediate said spaced side bars at the side of said laterally offset portion, and a laterally-extending portion on one of 80 said side bars for receiving the load. 85

7. In a conveyer, a link having end portions for pivotal connection with adjacent links, intermediate spaced side bars laterally offset, reinforcing struts intermediate the side bars at the offset portions thereof, and a load-supporting roller mounted between 90 said spaced side bars.

8. In a conveyer, a link having end portions forming hollow bearings for receiving the pivot pins attaching the same to adjacent links, laterally offset spaced side bars intermediate said end portions, reinforcing webs or struts intermediate said spaced side bars at the offsets therein, and a load-supporting roller mounted between said offset 95 100 side bars.

9. In a conveyer, the combination with a series of pivotally connected links, of a load-supporting roller mounted on one of said links intermediate the pivots thereof, 105 and a non-lubricated anti-friction journal bearing for said roller.

10. In a conveyer, the combination with a series of pivotally connected links, of a load-supporting roller for one of said links, 110 and a roller journal bearing for said load-supporting roller operable without lubricant.

11. In a conveyer, the combination with a series of pivotally connected links, of a 115 load-supporting roller for a link intermediate the pivots thereof arranged between spaced side bars of said link, a roller journal bearing for said load-supporting roller, and a pin extending between said spaced 120 side bars and clamped thereto, said pin forming the stationary race for said roller journal bearing.

12. In a conveyer, a link having end portions for pivotal connection with adjacent 125 links, spaced side bars intermediate said end portions, a load-supporting roller arranged between said spaced side bars, a roller journal bearing for said load-supporting roller intermediate the link pivots and retained from 130

endwise displacement by said spaced side bars, and a pin endwise insertable through aligned apertures in said spaced side bars and roller journal bearing, constituting the 5 stationary race with the latter.

13. In a conveyer, a link comprising end portions for pivotal connection with adjacent links, spaced side bars intermediate said end portions, a lug or bracket on one of 10 said side bars forming a half-bearing for receiving a load-carrying bar, a cooperating bearing secured to said half-bearing to clamp said load-carrying bar, a load-carrying roller arranged between the spaced side 15 bars of said link, and a pin insertable through aligned apertures in said side bars engaged by said cooperating bearing and held thereby from endwise displacement.

14. In a conveyer, a link provided with 20 end portions for pivotal connection with adjacent links, spaced side bars intermediate said end portions, a lug or bracket projecting laterally from one of said side bars constituting a seat or bearing for a load- 25 carrying bar, a load-carrying roller arranged intermediate said spaced side bars, a pin insertable through aligned apertures in said side bars forming the journal for said roller, the inner end of said pin having 30 a transverse slot therein, and a cap for clamping said load-carrying bar to said laterally projecting lug or bracket provided with a flange for engaging the slot in said pin to lock the same from endwise displacement.

15. In a conveyer, a link comprising integral hollow end portions for pivotal attachment to adjacent links and intermediate spaced lateral offset side bars, a lug or 40 bracket projecting laterally from one of said side bars, and forming a seat or bearing for a load carrying bar, a load-carrying roller arranged between said spaced side bars, an

anti-friction roller journal bearing for said load-carrying roller held from lateral displacement by said side bars, a pin insertable through aligned apertures in said side bars and said roller journal bearing, and a cap or bearing for clamping said load-carrying bar also engaging said pin to lock the same 50 from endwise displacement.

16. In a conveyer, a chain comprising alternate links, one of said links having offset hollow end portions for receiving the pivots connecting the same to the alternate 55 links and also having spaced side bars intermediate said end portions, a load-supporting roller mounted intermediate said spaced side bars, and a sprocket for driving said chain having teeth for engaging alternate 60 links only and cut away to provide clearance for said load-supporting rollers.

17. In a conveyer, a link provided with end portions for pivotal connection with adjacent links, spaced side bars intermediate 65 said end portions, a lug or bracket projecting laterally from one of said side bars and constituting a seat or bearing for a load-carrying bar, a load carrying roller arranged intermediate said side bars, a pin insertable 70 through aligned apertures in said side bars forming the journal for said roller, and a member for securing said load-carrying bar to said lug or bracket and for securing said pin from endwise movement.

18. In a conveyer, the combination with a series of pivotally connected links, of a load supporting roller centrally aligned with said links and mounted upon one of the links intermediate the pivots thereof, and a 80 sprocket for driving said links cut away in registration with said load supporting roller to provide clearance therefor.

In testimony whereof I affix my signature.

JESSE E. McBRIDE.
